UNITED STATES PATENT OFFICE.

OWEN M. CRUMLY, OF CARLISLE, IOWA.

COMBINED ROTARY VALVE.

Application filed April 5, 1926. Serial No. 99,860.

My invention relates to a truncated cone-shaped combined rotary valve for a four cycle type of internal combustion engine having a combustion chamber with exhaust and intake communications therewith and means whereby said communications are intermittently and alternately opened and closed.

The object of my invention is to provide a combined rotary valve of simple, durable and comparatively inexpensive construction.

A further object of my invention is to provide novel means for lubricating my rotary valve whereby oil is in continuous contact therewith and convenient means for replenishing the supply of lubricant.

Still a further object is to provide an easily operated and readily accessible device for preventing admittance of air into the fuel during the intake stroke.

Still a further object is to provide means driven by the engine for operating my improved valve.

Still a further object is to so construct and arrange the various parts whereby replacements are easily and quickly made and the valve is readily accessible for grinding the worn surfaces.

With these and other objects in view, my invention consists in the construction, arrangement and combination of the various parts of my invention, whereby the objects contemplated are attained, as hereinafter more fully set forth, pointed out in my claims, and illustrated in the accompanying drawings, in which:

Figure 1 is a vertical transverse sectional view of an internal combustion engine illustrating my combined-rotary-valve mounted theron.

Figure 2 is a detailed view in perspective of the valve-casing.

Figure 3 is a bottom plan view of the valve only.

Figure 4 is a top plan view of a pressure device used in connection with my valve.

Figure 5 is a side elevation of the pressure device; and

Figure 6 is a perspective view of a key or keeper used in my valve construction.

On the drawing I have used the reference numeral 10 to indicate generally a four cycle internal combustion engine.

A valve casing 11 is an extended portion, or an integral part, of the engine head 12 and may be suitably positioned adjacent the

combustion chamber 13 to minimize the travel of gas between the combustion chamber and the valve proper 14. The valve-casing 11 has adjacent the combustion chamber 13, an aperture or port 15 having communication with the combustion chamber 13 through a passage 16.

It will be noted by referring to Figure 1 that the upper portion of the valve casing 12 is bored cylindrical as at 17 with vertical sides and is bored in the shape of a truncated cone as at 18 for the reception of the truncated cone shaped valve 14. It is therefore obvious that the lower the valve 14 is in the casing 12, the tighter it will be for providing gas tight joints to prevent admittance of air to the fuel during the intake stroke.

The upper end of the valve-casing 12 is internally screw-threaded as at 19 and is externally screw-threaded as at 20.

A pressure device comprising a horizontal ring 21, externally screw-threaded, and a vertical ring 22 is received in the upper end of the casing 12. The threads on the ring 21 coact with the threads 19 of the casing 12 whereby the pressure device may be vertically adjusted relative to the casing 12 by screwing it inwardly or outwardly. The rings 21 and 22 form what might be called a cage. A rod 23 is slidably received in the upper portion of the ring 22 and has an enlarged end 24 slidably received in the lower portion of the ring 22. The end 24 is rectangular in cross section and fits through a rectangular opening 22a in the ring 22 whereby the rod 23 does not rotate. A coil spring 26 is carried by the rod 23 and is interposed between the enlarged end 24 thereof and the upper portion of the ring 22 whereby the point 25 on the end 24 is constrained to move in a downward direction. This movement of the rod 23 is transmitted to the valve 14 by the point 25 coacting with a depression 27 in the top of the valve whereby the valve 14 at all times snugly fits within the valve casing 12.

From the foregoing it will be seen that an adjustable spring pressure may be applied to the valve 14 by screwing the pressure device up or down in the casing 12. The portion 17 of the valve casing 12 may be cylindrically bored as illustrated or may be made in any suitable form.

For locking the pressure device against rotation after it has been adjusted, I provide a key 28 slidably mounted in a dove-

tail groove 29 in the ring 22 and having a lug 30 for selectively coacting with one of a plurality of notches 31 in the upper end of the casing 12. After the pressure device 5 has been tightened so that the spring 26 exerts the desired pressure on the valve 14, the groove 29 is brought in alignment with one of the notches 31 and the key 28 inserted in the groove 29 with the lug 30 10 engaging the notch 31.

I provide a cap 32 for enclosing the upper end of the valve casing 12. The cap 32 is interiorly screw-threaded as at 33 for coacting with the threads 20 on the casing 12. The cap 32 is threaded as at 36 to receive a plug 37. The plug 37 has a recess 38 whereby said plug does not interfere with the action of the pin 23. A vent opening 39 is provided in the plug 37. The 15 space above the valve 14 and in the cap 32 form an oil cavity 14^a. Oil may be supplied to the cavity 14^a, by removing the plug 37. The oil in the cavity 14^a is always in contact with the top of the valve 14 and keeps the valve seat lubricated. By the removal of the cap 32 and the cage 21—22, the valve 14 may be removed from the valve casing 12 for replacement or for 20 grinding of the valve and seat. On the key 28 is formed a projection 28^a which is engaged by the cap 32 for preventing disengagement of the lug 30 from the notch 31 when the cap 32 is in place.

At the central portion of the valve proper 25 14 and in radial alignment are ports 40 and 41. The port 41 is the exhaust port and the port 40 is the intake port.

From the foregoing it will be seen that the port 15 forms a dual purpose port and, 40 being in alignment with the ports 40 and 41 it provides a means of ingress and egress for gas from and to the ports 40 and 41.

A second intake port 42 is provided in the valve 14 which is diametrically opposite the port 40 but spaced vertically on the valve relative to the port 40. A second exhaust port 43 is provided diametrically opposite the port 41 and spaced vertically therefrom, and also from the port 42.

50 Passage ways 48 and 49 are provided in the valve 14 between the ports 40 and 42 and the ports 41 and 43 respectively. The passages 48 and 49 are curved as shown so that one does not interfere with the other.

An intake port 44 and an exhaust port 45 are provided in the casing 12 and are in alignment with the ports 42 and 43 respectively. An intake manifold 46 supplies fuel to the port 44 and an exhaust manifold 47 provides means for egress of exhaust gas through the port 45.

In the operation of my combined-rotary-valve, the intake passage 48 intermittently provides a means of communication between the intake manifold 46 and the combustion

chamber 13. The exhaust passage 49 intermittently provides means of communication between the combustion chamber 13 and the exhaust manifold 47.

It will be noted by referring to Figure 2 70 that the ports 44 and 45 are longer circumferentially of the valve than the port 15. The purpose of this is so that ports 42 and 43 in passing ports 44 and 45 will maintain the passage ways 48 and 49 completely 75 open while ports 40 and 41 are passing port 15. The port 15 in conjunction with ports 40 and 41 therefore serves to time the valve and the length of these ports determine the length of time the passages 48 80 and 49 are open to the combustion chamber 13. The port 15 is approximately one-half the length of the ports 40 or 41. The valve 14 is rotated one revolution during the complete engine cycle. The timing of the 85 respective passages; namely, intake and exhaust, is determined by the manufacturer and is attained by making the respective ports 40 and 41 of adequate length, in the line of the rotation of the valve 14, relative to the length of the port 15, so as to produce the requisite time of opening or closing the passages 48 and 49, respectively. The valve 14 has a recess 50 in the bottom end thereof and may be rotated by the usual cam shaft 51 through the medium of any suitable system of gearing. In Figure 1, I have illustrated a vertical drive shaft 52 driven from the shaft 51 by intermeshing 90 bevel gears 53 and 54. A tongue 55 on the upper end of the shaft 52 coacts with the recess 50 whereby rotation of the shaft 52 will rotate the valve 14 and said valve may be vertically adjusted and still remain in operative engagement with the shaft 52.

The valve 14 rotates in the direction indicated by the arrow 56, but may be made to be rotated in the opposite direction, by exchanging the ingress and egress of gases.

My valve may be operated perpendicularly, as illustrated, or horizontally or in any intermediate position. The extra combustion chamber space requisite for operation of my valve is only that of the passage 16 which can be even less than that shown on the drawing. My invention as illustrated in the drawings, is in conjunction with an engine having one cylinder but it is obvious that one valve assembly may be applied to each cylinder of engines having a plurality of cylinders.

One feature of the invention is embodied in the convenience of the combined-rotary-valve being readily accessible as previously described without necessitating the removal of the head 11 of the engine 10. It is also obvious that I have provided novel and efficient means for adjusting and lubricating my improved valve.

Some changes may be made in the con-

struction and arrangement of the various parts of my invention, without departing from the real spirit and purpose of my invention and it is my intention to cover by 5 my claims, any modified forms of structure or use of mechanical equivalents, which may be reasonably included within their scope.

I claim as my invention:

1. A combined rotary valve for four cycle 10 internal combustion engines comprising a valve casing having a truncated cone shaped opening, a truncated cone shaped valve rotatably mounted therein, the top of said valve being spaced below the top of said casing, a pressure device mounted in one end of said casing and comprising a cage like device, threaded to coact with threads in said valve casing, a pin slidably and non-rotatably mounted in said cage, notches in 15 said casing, a dovetail groove in said cage, a key slidably mounted in said groove, a lug on said key for coacting with one of said notches, a cover for said valve casing, a portion of said key adapted to be engaged by 20 said cover, an opening in said cover, whereby lubricant may be supplied to the space above the valve and a plug for said opening.

2. A combined rotary valve for four cycle 25 internal combustion engines comprising a valve casing having a truncated cone shaped opening, a truncated cone shaped valve rotatably mounted therein the top of said valve being spaced below the top of said casing, a pressure device mounted in one end of said 30 casing and comprising a cage, a pin slidably and non-rotatably mounted in said cage, notches in said casing, dovetail groove in said cage, a key slidably mounted in said groove and having a portion adapted to coact with one 35 of said notches, a cover for said casing, a projection on said key adapted to be engaged by said cover.

45 3. A combined rotary valve for four cycle

internal combustion engines comprising a valve casing having a truncated cone shaped opening, a truncated cone shaped valve rotatably mounted therein, the top of said 50 valve being spaced below the top of said casing, exhaust and intake passages in said valve, an exhaust and an intake port in said casing, each coacting with one end of said passages and a dual purpose port coacting 55 with the other end of said passages, a pressure device mounted in one end of said casing and comprising a cage threaded to coact with threads in said valve casing, a pin slidably and non-rotatably mounted in said 60 cage, notches in said casing, a dovetail groove in said cage, a key slidably mounted in said groove, a lug on said key for coacting with one of said notches, a cover for said valve casing, a portion of said key adapted 65 to be engaged by said cover, an opening in said cover, whereby lubricant may be supplied to the space above the valve and a plug for said opening.

4. A rotary valve for engines comprising 70 a tapered valve casing, a tapered valve therein and a pressure device comprising a cage adjustably received in said casing, a spring actuated pin supported by said cage and engaging the large end of said valve, notches 75 in said casing, a dovetail groove in said cage, a key slidably mounted in said groove and having a portion adapted to coact with one of said notches, a cover for said casing, a projection on said key adapted to be engaged 80 by said cover.

5. In combination with a rotary valve having a casing and a valve therein requiring a spring pressure thereon, a pressure device comprising a cage mounted longitudinally adjustable in one end of said casing, a spring actuated pin supported by said cage and engaging said valve, means for locking the adjustment of said cage comprising a key coacting with said cage and said casing. 85
